TEMPORARY BATHTUB COVER

Filed Feb. 21, 1931

INVENTOR

George M. Gould
BY E. J. Lennert
ATTORNEY

UNITED STATES PATENT OFFICE

GEORGE M. GOULD, OF BROOKLYN, NEW YORK

TEMPORARY BATHTUB COVER

Application filed February 21, 1931. Serial No. 517,541.

My invention relates to temporary covers for bath tubs to protect the color, glazing or finish of the same when positioned in a room before the plastering, tiling or painting is done; and the objects of my improvement are, 5 first, to provide a strong yet light weight cover having aprons and plates so adjustable that every part of the bath tub, both in and outside, is completely covered, concealed and protected against any damage; a further object is to provide such a cover with suitable 10 adjustable gauges or guides for surfacing the plaster wall finish or for setting the tiling on or against the tub.

15 In the accompanying drawing

Fig. 1 is a perspective view of my improved cover on a bath tub, set in a recess;

Fig. 2 is a front elevation, partly in longitudinal centre section, one section of the 20 apron being removed for clearness of illustration, the upper plate extensions being set for the plastering of the wall;

Fig. 3 is a cross sectional view on line X—X of Fig. 2;

25 Fig. 4 is an enlarged detail of an upper adjustable extension plate set as a gauge or guide for tiling, and Fig. 5 is a perspective view of the end of a cover and apron when the tub is placed in a corner with one end exposed.

Similar reference characters refer to like parts in the several views.

The flat upper cover, 1, is an elongated body of an approximate size of the tub on which it is to be used, and is made of several 35 layers of thin wood, cross grained and glued together, commonly known as "panel boards"; to give it additional strength and rigidity and to prevent warping wooden strips, 2 2' are fastened respectively at longitudinal centre and near the ends, as shown, the centre strip, 2 extending further outwardly from the board than the two other strips. Two wire rods, 3 3', suitably anchored in the outer strips pass over the centre strip thus forming, when taut, a brace to strengthen centre and support any ordinary weight liable to be placed upon the cover, this construction being substantially similar to 40 that disclosed in Letters Patent Number

1,709,806, granted to me on February 3rd, 1931.

When desired the locking means, L, described and claimed in said Letters Patent may be used, as shown in Figs. 2, 3, though this feature forms no part of the present invention except as a combination for locking the cover in position; any other means which suitably locks or holds the cover in place may be used.

The front of the bath tub, B, is protected by an apron composed of two sheet metal plates, 7, 7', one overlapping the other, and of the approximate length of the tub and preferably about one inch above the floor, F, 60 to permit the laying of floor tiling against the tub; a plurality of slots, 7'', through which screws, 8 pass, are provided whereby the apron is held in an immovable position by thumb nuts, 9.

A right angle metal strip 4, fastened to the upper outer edge of the cover, 1, overlaps the sheets 7, 7', and holds them suspended by screws 5 and thumb nuts 6, which are fastened in the aprons and travel in horizontal slots 4' 65 in the angle strip 4, to permit horizontal adjustment.

When a tub is placed in a recess, as in Figs. 1, 2, adjustable extension plates, 10 are used, one on each end; a right angle bend, 10', 70 at the inner edge tends to stiffen the plate. These plates are adjustable by slots, 11, for the passage of screw, 12, and held in place by thumb nuts, 13, and form gauges or guides for the plasterer or tile setter. T is tile.

The guides or gauges 10 are in close proximity to the ends of the body or cover which has a flat unobstructed upper surface which facilitates cleaning the cover of sand, paint, plaster, or the like which may lodge upon it. 75 The gauges 10 can be adjustably secured in place and enable the tile setter to accurately set tile to a straight even line.

When cover is to be used on a "corner tub" a protecting end plate, 14, bent at right angles at top, 14'' and front, 14' is used, this end piece being held in place by screws 15 and thumb nuts 16, as shown in Fig. 5. On the under side of the cover, 1, a narrow piece of felt or rubber, 1', is fastened so that it rests 80 85 90 95 100

on the glazed surface of the tub to prevent scratching or injury to the surface.

Such being the construction, the operation is as follows: When a bath tub has been set 5 on the floor and connected up with the water supply and waste pipes, the entire exposed surface is protected against any injury by any subsequent workman by placing and preferably locking the cover, 1, on the tub 10 at a point to suit the rear wall; the upper extension plates are advanced to the plaster line, and the apron sheets on the front are also adjusted and fastened to align with the wall, W. When the plastering is finished, 15 the upper extension plates are removed and any loose dirt or plaster is cleaned off and the plates replaced and fastened as a gauge or guide for the tile setter, as in Fig. 4. The tile setter can stand on the cover and also 20 have his material there without any danger of destroying the finish or surface of the tub.

When the work is finished, the cover is removed to be used elsewhere, leaving the tub clean and unsullied in any manner. The slotted aprons and the slotted extension plates 25 permits the cover to be used on several lengths of bath tubs, the height of the aprons being selected to suit the height of the tub on which they are to be used. The cover, 30 being made in sections and light in weight, the several parts are easily "knocked down" for shipping and transportation.

Such being my invention what I claim is,

35 1. A cover for a bath tub comprising a relatively light elongated flat body, guide plates adjustably secured at each end thereof and an apron adjustably secured to and suspended from said body whereby a bath tub is completely enclosed.

40 2. A closure for bath tubs comprising a relatively light elongated flat body, truss means at the under side of said body, lateral straight edge guide plates on the upper surface of said body, adjacent to the ends thereof of adapted to be adjusted towards or from a wall, and an apron suspended from said body, whereby the entire bath tub is effectively enclosed.

45 3. A closure for bath tubs comprising a relatively light body having truss means on the under side thereof, lateral angle plates adjustably mounted on the upper surface of said body and adjacent to the ends thereof, and a sectional apron secured to and suspended from said body, said apron having means for manual horizontal adjustment in 55 relation to each section.

GEORGE M. GOULD.
